Primary Examiner — Freda S Nunn(74) *Attorney, Agent, or Firm* — Marger Johnson; Andrew J. Harrington(57) **CLAIM**

The ornamental design for a stacking system support for electronic equipment, as shown and described.

DESCRIPTION

FIG. 1 is a perspective view of a stacking system support for electronic equipment showing our new design;

FIG. 2 is a perspective view thereof in a second position;

FIG. 3 is a top view thereof;

FIG. 4 is a front view thereof;

FIG. 5 is a rear view thereof;

FIG. 6 is a left side view thereof; and,

FIG. 7 is a right side view thereof.

The portions of the stacking system shown in broken lines form no part of the claimed design.
